HAND LOOM

Johan Carl Iwald, Rorosjon, Sweden

Application June 17, 1949, Serial No. 99,827
In Sweden April 25, 1947

3 Claims. (Cl. 139—29)

1

My invention relates to hand looms, and the object of the invention is to provide mechanism involving certain advantages the nature of which will appear from the following description in connection with the annexed drawing wherein Fig. 1 illustrates a side elevation of part of a loom with my improved mechanism, and Fig. 2 is a fragmentary end elevation looking from the left in Fig. 1.

In the drawing, numeral 10 indicates one of the two side frames of the loom. Numeral 11 denotes the slay beam having the reed 15. At both ends, the slay beam 11 is connected to two bars 12, 12a which at their other ends are interconnected by pivots indicated at 16a. Each pivot 16a engages the crank 13 of a rod which extends crosswise between the two side frames 10. A link 14 is pivoted at the lower end 17 to the lower bar 12a and pivoted at the upper end 18 to a portion of the side frame 10. Numeral 19 indicates diagrammatically the upper portion of the shaft motion mechanism.

In operation, the slay beam 11 together with the bars 12, 12a constitutes a reciprocating unit which is moved between the positions indicated in full lines and dotted lines, the members 13 and 14 performing swinging movements about their upper fulcrums. With a certain ratio between the lengths of the crank 13 and link 14, and if the pivot 17 is located at a certain point of the lower bar 12a, the beam 11 will be moved along a straight horizontal path, and the reed 15 will be located at right angles to the warp when the weft is about to be beaten up. The above-named ratio can be easily determined mathematically. For instance, if the pivot 17 is located exactly midway between the rod 16 and the beam at the end of the lower bar 12a, the length of the crank 13 should be half the length of the link 14, in order to secure straight movement of the slay beam.

It will be understood that a similar mechanism is arranged at the other side frame.

From above description it will be apparent that, as a result of the provision of the members 13 and 14, proper movement of the slay beam is secured in spite of the very short length of the links 14.

What I claim is:

1. In a hand loom, two side frames, a reciprocating unit including a slay beam and substantially horizontal bars fixed at one of their ends to said beam, crank-like members pivotally

2

mounted near the other ends of said bars, and pivotally mounted in said side frames above the plane of said horizontal bars, and suspending links for said unit, each link being at its lower end pivotally secured to one of said bars at a point between said beam and said member and being at its upper end pivotally secured to one of said side frames.

2. In a hand loom, two side frames, a reciprocating unit including a slay beam and substantially horizontal bars fixed at one of their ends to said beam, crank-like members pivotally mounted near the other ends of said bars, and pivotally mounted in said side frames above the plane of said horizontal bars, and suspending links for said unit, each link being at its lower end pivotally secured to one of said bars at a point between said beam and said member and being at its upper end pivotally secured to one of said side frames, the ratio between the length of said crank-like members and said links and the location of said point being such as to have said beam move along a straight horizontal path.

3. In a hand loom, two side frames, a reciprocating unit including a slay beam and substantially horizontal bars fixed at one of their ends to said beam, crank-like members pivotally mounted near the other ends of said bars, and pivotally mounted in said side frames above the plane of said horizontal bars, and suspending links for said unit, each link being at its lower end pivotally secured to one of said bars midway between said beam and said member and being at its upper end pivotally secured to one of said side frames, the length of each of said crank-like members being half the length of each of said links.

JOHAN CARL IWALD.
